UNITED STATES PATENT OFFICE.

PETER BARGION AND JAMES A. MORRELL, OF RICHMOND, INDIANA.

IMPROVEMENT IN APPARATUS FOR EVAPORATING SACCHARINE LIQUIDS.

Specification forming part of Letters Patent No. 39,490, dated August 11, 1863.

To all whom it may concern:

Be it known that we, PETER BARGION and JAMES A. MORRELL, of the city of Richmond, county of Wayne and State of Indiana, have invented new and useful Improvements in Saccharine-Evaporators; and we do hereby declare that the following is a full and exact description of the construction and operation of the same, reference being had to the annexed drawings, making a part of this specification, in which—

Figure 1 is a perspective view. Fig. 2 represents the flues of our furnace with dampers, and apertures, &c. Fig. 3 is also a partial representation of the same. Fig. 4 represents the back side of the flues. Fig. 5 represents a large evaporating-pan. Fig. 6 represents a water-tank. Figs. 7 and 8 represent evaporating-pans. Fig. 9 represents a filterer. Fig. 10 represents a cooler. Fig. 11 also represents the same, a cooler with one side taken off. Fig. 12 represents a strainer. Fig. 13 represents a side elevation of our furnace. Fig. 14 is a ground plan of our furnace.

A in Fig. 1 is the furnace, built of brick, with a chimney at the back end. B is a large evaporating-pan, as set on the brick-work and immediately over the fire. C C are two smaller evaporating-pans, placed at each side of the water-tank D, and at the back end of the large pan B, and should be set lower than the pan B, so that the contents of the pan B may be transferred to them. D is a water-tank placed between the large pan B and the chimney. E E is a filterer on each side of the furnace. F is a cooler. G in Fig. 11 represents a water-chamber in the same figure when the cooler F has one side taken off. H H H in Fig. 1 represent dampers or slides for admitting air. J J are divisions and slides in the pans C C. M is a strainer extending across the pan B. N is a spout or tube inserted in the side of the tank D for the purpose of supplying water to the pans C. O O are two spouts, one in the end of each of the pans C C, through which the contents of the pans C C may be passed into the filterers E E, and having passed through the filterers and pass down the coolers F (there being one on each side of

the furnace) into the pans 8 8. P is a tube in the front end of the water-tank through which water may be passed into the pan B. Q Q show the inner ends of two tubes inserted in the back end of the pan B, through which the contents of the pan B may be passed into the pans C C. R R are polygonal divisions in the pan B. 6 6 are slides in the divisions R R. 8 8 are two pans, one on each side of the brick-work of the furnace. 3 3 are handles of the dampers. 9 is one of the handles of the damper U. x x are holes to let cold water in and out of the cooler F.

Fig. 2 represents a section of the furnace cut off on a line with the dampers crosswise in this figure. V is the aperture through which the products of combustion pass into the chamber A⁵², and into the recess A⁵⁰, and through the passage T and up the chimney A⁵. W and X of Fig. 2 also represent two apertures through which the products of combustion may be passed into the chambers A⁵¹ A⁵¹, (for the purpose of supplying heat to the pans C C, as seen in Fig. 1,) and passing into the recesses A³ and A⁴ passes behind the upright pieces S S, and through the openings X X into the recess A⁵⁰, and through the aperture T and up the chimney A⁵. 2 2 2 2 2 are arrows showing the direction of the products of combustion. Y and Z are apertures to admit air for the purpose of graduating the heat in the chambers A⁵¹ A⁵¹. A¹ and A² are apertures for the same purpose as Y and Z. H H H are slides for the purpose of closing or opening the apertures A¹ A² and Y and Z. I I are dampers for the purpose of closing the openings W and X. 3 3 3 3 are rods to which the dampers W and X are attached, and for the purpose of adjusting the same. U is a damper attached to a rod, which is operated by the handles 9 9, for the purpose of closing the aperture b. A⁵ is the chimney with the front side taken off.

Fig. 3 is intended to give a better understanding of the flues in Fig. 2, A⁶ being the chimney with the front side taken off; T, the flue; S S, uprights; 2 2 2, arrows; A⁵¹ A⁵¹ A⁵² already described.

Fig. 4: A⁷ shows the back of chimney, and also shows the back of the recesses A³, A⁴,

and A⁵⁰. L is an opening in the recess A⁵⁰, provided with a sliding damper, K, which we call a "waste-damper." A¹A² are apertures, as shown in Fig. 2. H H are slides for closing the same.

Fig. 5: B, a pan, in which R R represent polygonal divisions; M, a strainer extending across the pan from side to side; Q Q, tubes or spouts for drawing the liquid from the pan.

Fig. 6: D is the water tank; N N, tubes or spouts for drawing off water. P is also a tube for the same purpose.

Figs. 7 and 8: C C are two pans, as seen at Fig. 1 at C C; J J, divisions. O O are spouts or tubes.

Fig. 9 is a filterer; E, the filterer; 4, a strainer at the top. 5 shows a part of one side of the filterer taken off, in order that charcoal made of beans and other grains or substances containing the most amyloid may be seen, the filterer being filled with said charcoal. Y is a spout.

Fig. 10: F represents a cooler. X X are holes to admit cold water and draw it off.

Fig. 11: F, the cooler with one side taken off, showing a chamber, G, called a "water chamber."

Fig. 12: A⁸ is a strainer, open on one side and made to fit into the filterer E at the spout on the right-hand side of said filterer.

Fig. 13 is a side elevation of the furnace, in which A is the fire-place.

Fig. 14 is a ground plan of the furnace; A, the fire-place; B, the grate-bars; A⁵¹ A⁵¹ A⁵², chambers for the passage of products of combustion; T, chimney-flue. A³ and A⁴ are recesses leading into the flue T.

The furnace may be constructed of brick or other suitable material, and may be secured from cracking by any of the well-known means, as bars of iron secured by nuts and screws, &c. An iron frame may be inserted in the front wall to which may be hung a door on hinges.

The large pan B may be made of galvanized iron. The sides may be formed by turning up and riveting the corners or by riveting them onto the bottom. After the pan is formed we insert the polygonal divisions and rivet each end of them to the sides of the pan, leaving a space in the middle to be closed by a slide, the grooves of which we form by riveting onto each side of the open space a piece of sheet-iron which forms the grooves for the slides 6 6. The slides are made by cutting a piece of sheet-iron the right size and bending over the top edge so as to form a handle. The strainer M is made by perforating a piece of sheet-iron or tin with small holes. It should belong enough to reach across the pan and be riveted at the ends and onto the bottom of the pan, as also should the polygonal divisions. The small pans C are made in the same way, only that the divisions are straight and lengthwise of the pans.

The filterer is made of sheet-iron, and may be riveted together, and should be made in two upright chambers connected at the bottom, with a strainer at each top end. The filterer should be filled with charred beans, or other grains or substances containing the greatest quantity of amyloid. The cooler F may be made in any form, so that there is a chamber to hold cold water and a rough surface made to retard the motion of the fluid as it passes down while the cooler is set slanting. We have adopted for the present the form of steps with the water-chamber below and attached to them. This may be made by riveting together an oblong box of suitable length and riveting strips on one side of it.

The tank D may be riveted together, and should be high enough to extend above the pans.

The slides H H H H are worked in grooves formed of sheet-iron and secured to the wall.

The dampers are made in the well-known way of securing a piece of sheet-iron on an iron rod, and may turn in staples driven in the wall.

Operation: It will be seen that by placing the large pan B over the furnace A, and the two small pans C C over the passages A⁵¹ A⁵¹, and by placing the tank D over the space A⁵², and by setting the filterers under the spouts O O, and the cooler F under the spout of the filterer, the evaporator is arranged for operation, the large pan B being supplied with cane-juice as the boiling progresses, and at the proper time it is strained through the strainer M, and is led into the pans C C through the tubes Q Q, where the boiling process is finished, during which the heat under the finishing-pans is graduated by means of the dampers i i and the slides H H H H, the dampers admitting heat and the apertures Y Z and A' A² admitting cool air at pleasure of the operator. When the boiling is finished it is passed out through the tubes O O into the filterers E E, through which it is filtered and runs down the coolers into the pans 8 8.

We do not claim the use of a furnace nor of evaporating-pans, as they are well known and have long been in use.

We do not claim the use of a water-tank separate and distinct; neither do we claim it in connection with the simple pans. We do not claim the use of a cooler, as they are well known; neither do we claim the use of any particular number of pans; but

What we do claim as our invention, and desire to secure by Letters Patent, is—

1. The combination of the strainer M, polygonal divisions R R, and pan B.

2. The arrangement of the pan B, with its polygonal divisions R R, in combination with the pans C C, when used in combination with the chambers A⁵¹ A⁵¹ A⁵², damper K, openings A' A², and Y and Z, and I I, and U.

3. The arrangement of the chambers A⁵¹

A^{51} A^{52} , in combination with the damper K, and openings A' and A^2 and Y and Z, and the dampers II and U.

4. The combination of the cooler and filterer when constructed, arranged, and operated substantially as above described.

5. The tank D, when used in combination with the pans B and C C, and chambers A^{51} A^{52} , damper K, openings A' A^2 , and

Y and Z, and II, and U, the whole being constructed, arranged, and operated substantially as above described.

PETER BARGION.
